UNITED STATES PATENT OFFICE.

CHARLES DE QUETTEVILLE WHITTLE, OF KENILWORTH, ILLINOIS, ASSIGNOR TO ALFRED VESTER SONS, INC., OF PROVIDENCE, RHODE ISLAND, A CORPORATION OF RHODE ISLAND.

DESIGN FOR A WALL PLATE FOR LIGHTING FIXTURES.

Application filed December 14, 1925. Serial No. 15,746. Term of patent 7 years.

To all whom it may concern:

Be it known that I, CHARLES DE QUETTEVILLE WHITTLE, a citizen of the United States, residing at Kenilworth, in the county of Cook and State of Illinois, have invented a new, original, and ornamental Design for Wall Plates for Lighting Fixtures, of which the following is a specification, reference being had to the accompanying drawing, forming part thereof.

Fig. 1 is a front view showing my new design.

Fig. 2 is an edge view.

I claim:

The ornamental design for a wall plate for lighting fixtures, as shown.

C. DE QUETTEVILLE WHITTLE.
